FIRING AND SAFETY MEANS FOR
BREAKDOWN FIREARMS

Alfred Curci, New Haven, Conn.

Application January 10, 1947, Serial No. 721,189

21 Claims. (Cl. 42—41)

1

The present invention relates in general to breakdown firearms, that is to say, firearms of the class in which the butt-unit and barrel-unit are pivoted together for relative movement to permit loading and unloading of the firearm, the invention relating especially to superior safety-means for automatically guarding against the accidental or unintentional discharge of the firearm.

The present application is a continuation-in-part of the co-pending application of Alfred Curci, Serial No. 579,083, filed February 13, 1945, and now abandoned.

An object of the invention is to provide superior fire-control means for a breakdown firearm.

A still further object is to provide a breakdown firearm with improved fire-control mechanism in which superior safety-means is embodied for preventing inadvertent discharge of the firearm, due to a sudden jar or shock.

A still further object of the invention is to provide superior safety-means for a breakdown firearm whereby the fire-control means is automatically and positively locked each time the firearm is broken for loading and unloading.

A still further object of the invention is to provide superior firing-means for breakdown firearms.

A still further object is to provide superior safety-means cooperatively associated with the firing-means of a breakdown firearm, wherein the firing-pin is automatically retracted below the face of the standing-breech by the safety-means after each shot has been fired.

A still further object of the invention is to provide the fire-control mechanism of breakdown firearms with safety-means constituting an integral part of the trigger and arranged normally to be held positively in front of the firing-member so as to prevent the forward movement thereof to firing position, both by the action of a manually-operated safety-slide and by the action of a trigger-locking lever adapted to be automatically actuated by the top-lever whenever the firearm is broken.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken side elevation partly in sec-

2

tion of a breakdown type of firearm including the novel features of the present invention, the firing-means and fire-control mechanism being in the positions these parts assume immediately after the gun has been fired and the trigger has been released;

Fig. 2 is a similar view of the firearm shown in Fig. 1, but with the hammer held in its cocked position by the sear-trigger assembly and the latter locked by the safety-elements of the firearm;

Fig. 3 is a similar view of the firearm shown in Fig. 1 but with the hammer in its forward firing position and the sear-trigger assembly in the position it assumes when the trigger has been pulled and before the latter has been released;

Fig. 4 is an enlarged broken perspective view partly in section of the butt-unit showing the safety-means, firing-means and fire-control mechanism of the present invention;

Fig. 5 is a fragmentary plan view partly in section of the novel hammer-spring mounting-means of this invention;

Fig. 6 is a perspective view of the displaceable collar of the hammer-spring mounting-means shown in Fig. 5;

Fig. 7 is a perspective view of the trigger including the hammer-locking element associated therewith;

Fig. 8 is a perspective view of the sear;

Fig. 9 is a perspective view of the hammer;

Fig. 10 is a perspective view of the hammer-spring pilot; and

Fig. 11 is a bottom plan view of the operating-lever for unlocking the barrel-unit and butt-unit.

The particular breakdown firearm herein chosen for the illustration of the present invention includes two major units 15 and 16 respectively (see Figs. 1, 2 and 3), pivoted together for relative movement. The rear unit 15 of the firearm may, for convenience of description, be designated as the butt-unit and comprises as its main features a frame 17 having a buttstock 18 rigidly secured to the rear end thereof. The complementary front unit 16 of the firearm is designated as the barrel-unit and comprises as its main elements a barrel 19 and a forearm 20, the latter being removably secured to the underside of the barrel. The forward portion of the frame 17 is

substantially U-shaped in cross section and comprises a bottom wall 21 and spaced parallel side walls which extend upwardly from the bottom wall and provide an open recess or pocket 22 therebetween. The recess is adapted to receive the rear end of the barrel-unit and, more par-

Fig. 1 is a broken side elevation partly in sec-

ticularly, a rectangular barrel-coupling lug 23 formed integral with and depending from the underside of the barrel 19 at the rear extremity thereof.

The forward edge of the barrel-coupling lug is provided with a transverse semicylindrical bearing-surface 24, the forwardly-facing wall of which is adapted to engage and bear upon the periphery of a fulcrum-pin 25 extending transversely of the frame adjacent the forward end of its trough-shaped portion and having its respective opposite ends rigidly supported in the complementary side walls thereof.

The complementary side walls of the frame as well as the bottom wall thereof, merge at their rear ends into a tubular portion 26 having a forwardly-facing apertured standing-breech 27 against which the rear end of the barrel abuts when the firearm is closed. Extending rearwardly from the substantially-tubular portion of the frame are an upper butt-attaching tang 28 and a lower butt-attaching tang 29 respectively secured at their rear ends to a vertical spacing-block or -pillar 30.

Mounted upon the upper surface of the tubular portion of the frame is an operating-lever 31 having a cylindrically-contoured operating-post 32 (see Figs. 1, 2, 3 and 11), adapted to project downwardly through and to have a bearing in a substantially-vertical aperture 33 formed in the top wall of the tubular portion 26 of the frame. The said operating-post 32 is preferably an integral part of the operating-lever 31 and is provided with a radial notch 34 in its lower end having a substantially-square operating-shoulder 35 adapted to cooperatively engage the upper end of an operating-finger 36 which constitutes a substantially-vertical extension of a barrel-unit locking-member 37, the latter being mounted for pivotal movement upon a transverse pivot-pin 38 which extends crosswise of the tubular portion 26 of the frame and is rigidly supported by the respective opposite side walls thereof.

The barrel-unit locking-member 37 is provided with a forwardly-projecting locking-nose 39 adapted normally to extend through an aperture 260 beneath the standing-breech 27 of the frame 17 and to enter a locking-notch 40 formed in the rear edge of the barrel-coupling lug 23. To this end, a coil-spring 41 is provided and mounted, as shown, on a transverse pin 42 secured at its opposite ends in the respective spaced parallel side walls of the tubular frame 17. The spring 41 comprises an upwardly-and-forwardly-extending arm 43 adapted to engage in a recess 44 in the rear face of the barrel-unit locking-member 37 at a point immediately below the pivot-pin 38 of the latter. The opposite end of the coil-spring constitutes a leg 45 which extends rearwardly and is formed as an inverted V, the lower extremity of which is adapted to engage in a notch 46 formed in the upper surface of the lower butt-attaching tang 29. In accordance with this construction, the force of the coil-spring 41, acting through its forward arm 43, normally resiliently holds the locking-nose 39 of the locking-member 37 forwardly in the notch 40 of the barrel-coupling lug 23. However, by turning the operating-lever 31 in a counterclockwise direction, which is the conventional direction of rotation of the operating-lever for unlocking the butt-unit from the barrel-unit, the operating-shoulder 35 of the operating-lever post 32 is adapted to engage and displace the operating-finger 36 of the barrel-locking member 37 forwardly, thereby moving the

locking-nose 39 of the locking-member rearwardly out of the notch 40 of the barrel-coupling lug 23 against the restraining force of the spring-arm 43, so as to permit the barrel-unit 16 to be rotated about the fulcrum-pin 25 relative to the butt-unit 15 for loading and unloading the firearm. During the relative rotation of the barrel-unit and butt-unit, commonly referred to as the "breakdown" of the firearm, suitable means hereinafter described is actuated to cock the firing-member. Ordinarily the operating-lever 31 will be released immediately following the breakdown of the firearm, whereupon the restraining force of the spring-arm 43 will swing the locking-member 37 back to its normal position, simultaneously returning the operating-lever 31 to its normal position in substantial alignment with the longitudinal axis of the firearm. As the barrel is swung back again to its normal position, its locking-lug 23 will engage the nose 39 of the locking-member 37, camming the latter rearwardly until its nose 39 is opposite the notch 40 of the barrel-locking lug 23, whereupon the detent action of spring 41 snaps the nose 39 back into the locking-notch 40 of the barrel-lug 23 to securely hold the barrel in its normal firing position.

Referring again to the operating-post 32 of the operating-lever 31, the lower end of the post is provided with a horizontal slot 47 which is substantially diametrically opposite the notch 34 thereof and intersects the peripheral wall of the post. The longitudinal axis of the slot 47 is parallel roughly to the longitudinal axis of the operating-lever, while the spaced parallel upper and lower walls 48 and 49 respectively thereof are substantially parallel to the underside of the top butt-attaching tang 28, for the purpose herein-after described. Extending substantially vertically through the forward end of the slot 47 and adjacent the outer edge thereof is a fixed pin 50.

Referring especially to Figs. 4 and 9 of the drawings, the firing-means of the firearm comprises a firing-member or hammer indicated generally at 51, comprising a head-portion 52 and a claw-portion 53. The head-portion 52 is shown provided with an upwardly-projecting tongue 520 arranged to engage in a guide-slot 280 formed in the upper tang 28, the front end wall of the guide-slot 280 constituting a fixed stop adapted to be engaged by the tongue 520 to limit the forward movement of the hammer 51. The claw-portion 53 of the latter is provided at its lower front corner with an integral transverse bushing 54 adapted to pivotally engage in the vertical slot 55 of a post 56 which is secured at its lower end in the lower butt-attaching tang 29, the vertical plane of the slot 55 substantially intersecting the longitudinal axis thereof. The aforementioned transverse pin 42 constitutes the pivotal means for securing the integral bushing 54 of the firing-member in the slot 55 and to this end extends transversely through the bifurcations of the slot 55, the outer extremities respectively of the pin 42 being firmly secured in suitable apertures in the corresponding side walls of the frame 17. Pivotally secured to the forward edge 59 of the head-portion 52 of the hammer is a firing-pin 60, the rear end of which is provided with an enlarged bifurcated head 61, the slot of which is adapted to receive the forward edge 59 of the hammer. A suitable pivot-pin 62 is provided for fastening the slotted head 61 of the firing-pin to the hammer, the forward end of the former being tapered to a slender point or nose 63 which is adapted to project through the aperture 64 of the

standing-breech 27 of the butt-unit when the hammer is in its forward firing position, as shown in Fig. 3, to fire the cartridge. In accordance with one of the novel features of this invention, in this position of the hammer, it is entirely relieved of the resilient force which drives the hammer forwardly from its cocked position to its firing position as a consequence of which the hammer is free to swing backwardly without restraint, as hereinafter described, and thereby to retract the nose of the firing-pin below the front face of the standing-breech, as indicated in Fig. 1.

Formed in the forward edge 59 of the hammer substantially immediately below the firing-pin 60, is a recess 590 comprising a downwardly-and-inwardly-sloping cam-surface 65, the upper end of which intersects the substantially-vertical forward edge 66 of the hammer. This vertical forward edge 66 immediately above the cam-surface 65 is hereinafter referred to as the "breast-portion" of the hammer. Formed integrally or otherwise secured to the claw-portion 53 of the hammer and preferably on its left-hand side, is a laterally-projecting cocking-lug 67. The latter constitutes one element of the hammer-cocking means and to this end is adapted to be engaged by the crank-arm 68 of a cocking-lever 69 which is pivotally supported at its rear end on the transverse pin 42 of the hammer, the opposite end of the cocking-lever extending forwardly through the aperture 260 beneath the standing-breech 27 into the substantially U-shaped portion of the frame forwardly thereof. Referring to Figs. 1, 2 and 3, the forward end 70 of the cocking-lever 69 is adapted to make an articulated connection with the rearwardly-extending end of a cocking-finger 71, the forward end of which is pivoted as at 72 to the fixed forearm 29 of the firearm, the finger 71 being seated in and extending rearwardly from its pivot-point 72 through a longitudinal slot 73 formed in the outer wall of the barrel-lug 23. It will be evident that when the barrel-unit 16 is pivoted downwardly with respect to the butt-unit 15, the rear end of the cocking-finger will engage and elevate the forward end 70 of the cocking-lever thereby pivoting the latter about its pivot-pin 42, whereby its crank-arm 68 is rotated clockwise, as seen in Fig. 4. Engagement of the upper end of the crank-arm 68 with the cocking-lug 67 of the hammer 51 will rotate the latter clockwise about its transverse pivot-pin 42 for cocking engagement with the sear of the fire-control mechanism hereinafter described.

Referring to Fig. 4, fixedly secured to the lower buttstock-tang 29 is a strut 74, the lower end of which is provided with a depending tenon 75 adapted to engage in a longitudinal axially-aligned trigger-slot 76 in the aforesaid tang, the tenon 75 being secured therein and at the rear end thereof by a pair of transverse pins or other equivalent fastening-means. The strut 74 has an upwardly-and-forwardly-extending reach 77 which is provided at its upper extremity with a longitudinal slot 78 in which the upper end of a trigger 79 is pivotally secured, as indicated at 80, the trigger 79 constituting one element of the fire-control means. The upper end of the trigger 79 is provided with a vertical slot 81 (see Fig. 7) which forms right and left bifurcations 82 and 83 respectively and in which a sear 84 is adapted to be assembled by the aforesaid pivot-pin 80. The sear 84 comprises a depending forwardly-projecting nose-portion 85 arranged normally to engage a sear-shoulder 86 of the hammer 51 to hold the latter in cocked position, as hereinafter de-

scribed and as shown in Fig. 2. The sear, and in particular its nose-portion 85, is adapted to be held in its forward position with respect to the trigger 79 by a resilient-means comprising a coil-spring 87 arranged to engage at its forward end in a notch 88 in the rear edge of the sear and at its rear end in a recess 89 formed in the bottom 90 of the trigger-slot 81. In order to limit the forward pivotal movement of the sear relative to the trigger and to provide means for positively retracting the sear-nose 85 from engagement with the sear-shoulder 86 of the hammer, the sear is mounted in the slot 82 of the trigger so as to be positively retracted rearwardly with the trigger when the latter is pulled, and also to be displaceable rearwardly in the slot independently of the trigger. To this end, the sear is provided with a laterally-extending lip 91 (see Figs. 4 and 8), which is adapted to overlie the upper rear edge 20 of the left-hand bifurcation 83 of the trigger, the lip 91 being provided with a substantially-square shoulder 92 on its underside adapted normally to be held in cooperative engagement with the adjacent rear face of the corresponding bifurcation 83 of the trigger by the force of the sear-spring 87. In accordance with one of the discoveries of this invention, the sear-spring may be and is preferably of relatively heavy construction so as to more nearly preclude accidental release of the hammer but is not, however, a factor in the weight of the trigger pull, the latter being governed by a trigger-spring 93 which is lighter than the sear-spring 87 and engaged at its forward end in a recess 94 in the back edge of the trigger 79 and at its rear end in a recess 95 in the forward edge of the strut 74. It will be evident that by pulling the trigger rearwardly against the restraining force of the trigger-spring 93, the engagement of the edge of the bifurcation 83 of the trigger with the shoulder 92 of the sear serves to positively withdraw the sear-nose 85 from the sear-shoulder 86 of the hammer to release the latter. On releasing the trigger, the compressed trigger-spring moves the trigger forwardly and raises the sear-nose up into the path of the hammer-sear shoulder 86, as indicated in Fig. 1. When the hammer is moved back into its cocked position, the bottom edge of the sear-shoulder 86 engages the nose-portion 85 of the sear and retracts the latter against the restraining force of the trigger-spring, the nose of the sear thereafter snapping into engagement with the sear-shoulder of the hammer to hold the latter in its normal cocked position, as shown in Fig. 2.

55 The hammer 51 is adapted to be urged forwardly from its cocked position to its firing position by the force of resilient-means comprising a coil-spring 96 which is mounted on a pilot 97 provided at its forward end, as shown in Figs. 4 and 60, 10, with a head-portion 98 slotted vertically to receive the rear edge of the hammer 51, the head-portion being secured thereto by a pivot-pin 99. The rear end of the head-portion constitutes a substantially-square shoulder 100 against which the forward end of the hammer-spring 96 engages. The rear portion of the spring-pilot 97 is provided with a reduced section 101 comprising two diametrically-opposite flat sides which form square shoulders 102 with the extreme rear end portion 103 of the spring-pilot. Referring to Fig. 6, straddling the reduced section 101 of the pilot is a disk-shaped collar 104 having a substantially-rectangular diametrically-disposed slot 105, the spaced parallel walls of which are adapted to slidely engage the flat sides of the reduced section

101 of the pilot and to bring up against the shoulders 102 thereof so as to limit the rearward displacement of the collar 104 thereon, whereby the latter constitutes a displaceable stop or shoulder for the rear end of the hammer-spring 96, as illustrated in Fig. 5. The rear extremity 103 of the spring-pilot is adapted to slidably engage in an aperture 106 formed in an upwardly-and-rearwardly-projecting leg 107 of the fixed strut 74.

In accordance with this construction, when the hammer is cocked its spring 96 is compressed between the shoulder 109 of the spring-pilot, as the latter moves rearwardly, and the displaceable stop or collar 104, which is now held immobile against the forward face of the leg 107 of the fixed strut 74; for, as clearly shown in Fig. 2, when the hammer is moved into its cocked position, the rearward displacement of the spring-pilot projects its rear extremity, including the shoulders 102 thereof, entirely through the guide-aperture 106 of the leg 107 to a position rearwardly of its rear face, as a consequence of which the spring load on the collar 104 is transferred from the shoulders 102 of the spring-pilot to the forward face of the leg 107. When the hammer is released, the force of the compressed spring 96 propels the hammer forwardly into its firing position (see Fig. 3) in which position the pilot is carried forward sufficiently to bring its shoulders 102 forwardly into engagement with the collar 104, thereby picking up the latter and moving it forwardly an appreciable distance out of engagement with the forward face of the leg 107. This position of the hammer is termed its "firing" position, in which position the point 63 of the firing-pin is projected beyond the face of the standing-breech 27 so as to strike and fire a cartridge in the barrel of the barrel-unit. Moreover, the firing-spring 96 no longer acts on the hammer to hold it in its forward firing position, since any residual compression force of the spring is now acting against the displaceable stop-collar 104 which, in turn, is in abutting engagement with the shoulders 102 at the rear end of the spring-pilot itself, as a consequence of which the hammer is relieved of any restraining force and may pivot freely rearwardly a distance corresponding substantially to the distance of the collar 104 from the forward face of the leg-strut 107 (when the hammer is in its firing position) and for the purpose hereinafter described.

Formed in the upper extremity of the leg 107 of the strut is a second aperture or slot 108 through which extends the rear end of a safety-slide 109, the rear end portion of which carries a coil-spring 110. The forward end of the safety-slide is engaged in the recess 67 of the operating-lever post 32, and is provided with a concave bearing-surface at its forward edge adapted to engage the eccentric pin 50 of the operating-lever 31. The force of the safety-slide spring 110, acting at its forward end against a shoulder 111 of the slide and at its rear end against the forward face of the leg 107, serves to hold the forward concave edge of the slide in engagement with the eccentric pin 50, thereby exerting a force on the operating-lever 31 to hold the latter in its normal inoperative position in substantially-axial alignment with the axis of the firearm, and to return the latter to its normal position after having been operated manually to unlock the barrel-unit. It will be noted, moreover, that the force of the safety-slide spring 110 also holds the slide 109 upwardly in contact with the underside of the top wall of the upper tang 28, whereby the forward end of the safety-slide constitutes, in

effect, a key for holding the post 32 of the operating-lever down in its aperture 33 in the top wall of the frame 17.

Pivotedly mounted as at 112 on the base-portion of the strut 74 and at the left-hand side thereof, is a trigger-locking lever indicated generally at 113 and comprising a forwardly-extending finger 114 which is adapted to be moved behind and into abutting engagement with a lug or shoulder 115 formed integrally with or otherwise secured to and projecting from the corresponding side of the trigger, to lock the latter. To this end, the trigger-locking lever 113 is provided with an upwardly-extending reach 116 having a nose-portion 117 at its upper end adapted to engage in a notch 118 formed in a conventional safety-slide 119 mounted on the upper tang of the butt-unit. It will be obvious that by moving the safety-slide rearwardly, the trigger-locking lever 113 will be pivoted clockwise, as seen in Fig. 1, so as to move the forwardly-extending finger 114 thereof into abutting engagement with the trigger-lug 115, as shown in Fig. 2, to effectively lock the trigger. Intermediate the upper and lower ends of the trigger-locking lever 113 is a rearwardly-extending arm 120 formed integrally therewith and provided at its rear end with a portion bent at substantially right angles and hereinafter termed a "bent" 121 which is back of the rear face of the strut-leg 107 and positioned substantially opposite the rear end of the safety-bar 109 and immediately adjacent thereto. The latter relationship is provided so that when the operating-lever 31 is rotated in the act of unlocking the barrel-unit and butt-unit, the pin 50 of the operating-lever post 32 will act to displace the safety-bar 109 rearwardly and hence push the rear end thereof against the bent 121 of the trigger-locking lever 113, as a consequence of which the latter is pivoted rearwardly or in a clockwise direction, as seen in Fig. 2, to elevate its finger 114 into engagement with the trigger-lug 115 to lock the latter. It will be noted that by actuating the operating-lever 31 to displace the safety-bar 109 and the trigger-locking lever 113 into trigger-locking position, mutual engagement of the nose-portion 117 of the trigger-locking lever in the notch 118 of the safety-slide 119 will suffice to automatically displace the latter from its forward "firing" position rearwardly to its "safe" position. Moreover, the safety-slide may be moved also from its firing position shown in Fig. 1, to its safe position as shown in Fig. 2, independently of the operating-lever to lock the trigger. As in conventional structures, the safety-slide is provided with a depending-prong 122 having a transverse pin 123 which is adapted to engage the underside of a safety-slide detent-spring 124, the latter being provided with a downwardly-projecting crimp on opposite sides of which the pin 123 of the safety-slide is adapted to engage in the forward and rearward positions respectively of the latter to hold the safety-slide 119 immobile in either position.

Referring again to Fig. 7, an additional feature of the invention is the provision of hammer safety-means associated with the fire-control mechanism for positively preventing the inadvertent discharge of the firearm despite the fact that the trigger has been locked by the safety-means hereinabove described. To this end, the trigger 79 is provided at its upper end with an integral forwardly-extending reach 125, the forward end of which is provided with a portion bent at substantially right angles and herein-

after termed a "bent" 126. The length of the reach 125 and the disposition of its bent 126 is such that when the hammer 51 is retracted to its cocked position, as shown in Fig. 2, the bent 126 is substantially opposite, but spaced forwardly of, the breast-portion 66 of the hammer, the forward spacing of the bent 126 being slightly less than the distance required for the hammer to reach its forward firing position. Thus, assuming the hammer is held in its cocked position by the locked sear-trigger assembly, as shown in Fig. 2, then in the event the nose 85 of the sear 84 should be inadvertently jarred off of the sear-shoulder 86 of the hammer, the latter would be released and swung forwardly until its breast-portion 66 struck the bent 126 of the locked trigger-reach. Thereupon the hammer would be stopped and positively held by the hammer safety bent 126 in a position slightly rearwardly of its firing position, as a consequence of which the nose 63 of the firing-pin would not extend through the aperture 64 of the standing-breach sufficiently to fire a cartridge in the barrel of the firearm. However, in the normal operation of firing the gun the bent 126 of the trigger-reach will be pivoted downwardly slightly as the trigger is pulled, to a position substantially opposite the recess 590 immediately below the cam-surface 65 in the forward edge of the hammer so that the latter and its firing-pin are permitted to move forwardly unchecked into firing position, as shown in Fig. 3.

The operation of the safety-mechanism firing-means and fire-control mechanism of the firearm may be described briefly as follows. Assuming that the hammer of the firearm is held in its cocked position by the sear 84, as shown in Fig. 2, and the safety-slide is in its "off" or "firing" position, then by pulling rearwardly on the trigger, the sear-nose may be positively disengaged from the sear-shoulder of the hammer to release the latter, whereupon it is swung forwardly forcefully by the compressed hammer-spring 96 to project the nose 63 of the firing-pin through the aperture 64 in the front face of the standing-breach 27 for firing a cartridge in the breech of the barrel. At the end of its forward movement which corresponds to its firing position, the hammer is freed of any restraint or resistance offered by the hammer-spring 96, in the manner described above, and hence is free to be moved back or retracted to its position, as shown in Fig. 1, wherein the displaceable collar 103 of the spring-pilot is brought up against the forward face of the leg 107 and the nose 63 of the firing-pin 69 is retracted below the front face of the standing-breach, thereby permitting the firearm to be unloaded and reloaded without the disadvantages and hazards which accompany a projecting firing-pin. The retraction of the hammer and firing-pin is effected upon releasing the trigger 79, the force of the compressed trigger-spring 83 serving to move the trigger forwardly, thereby elevating the bent 126 of its reach 125 into camming engagement with the cam-surface 65 of the hammer. Since the latter is unrestrained, it will thereupon be cammed rearwardly by the bent 126 as the latter rides up on and engages the breast-portion 66 of the hammer, as shown in Fig. 1, simultaneously retracting the nose-portion of the firing-pin below the forward face of the standing-breach. The operator may now operate the operating-lever 31 to unlock the barrel-unit from the butt-unit and swing the former downwardly relative to the latter without 75

encountering any untoward resistance or hazards. During this action, the articulated connection between the cocking-lever 69 and the cocking-finger 71 pivots the cocking-lever clockwise, as seen in Figs. 1, 2 and 3, so as to positively pivot the hammer 51 rearwardly to engage its sear-shoulder 86 with the forwardly-extending sear-nose 85, the bottom of the shoulder 86 engaging and retracting the spring-held nose of the sear during the initial movement of the hammer, to permit the sear-nose to snap into engagement with the shoulder 86 of the hammer and hold the latter in its cocked position. During the operation of the operating-lever 31 which, as pointed out above, suffices to rotate the barrel-unit locking-member 37 clockwise, to disengage it from the locking-notch 40 of the barrel-lock 23, the safety-bar 109 will be displaced rearwardly to automatically swing the trigger-locking lever 113 clockwise, so as to elevate its finger 114 into abutting engagement with the trigger-lug 115, to effectively lock the latter, the safety-slide 119 being simultaneously retracted to its "on" or "safe" position, and held therein by the safety-slide detent-spring. As a consequence, the trigger is locked and the hammer safety bent 126 is positively held in front of the breast-portion of the hammer so as to prevent the latter from moving forwardly to its firing position in the event the sear should inadvertently be jarred off the shoulder of the hammer. The firing-means and fire-control elements are again in position for firing the gun, which may be done whenever the safety-slide 119 is moved forwardly to its "off" or "firing" position, so as to lower its finger 114 out of locking engagement with the trigger-lug 115.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a breakdown firearm, the combination with a butt-unit and a barrel-unit pivoted for movement with respect to the said butt-unit; of locking-means for locking the two said units in normal axial alignment, including a manually-operated top-lever; a firing-member; means for urging said firing-member forwardly into firing position; fire-control means including a trigger, a firing-member stop-element integral with said trigger and arranged in the normal position of said trigger to extend in front of said firing-member and a sear carried by said trigger, said sear being arranged normally to engage said firing-member to hold the latter rearwardly in cocked position; and safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing position and the consequent discharge of said firearm by inadvertent disengagement of said sear from said firing-member.

2. In a breakdown firearm, the combination with a butt-unit and a barrel-unit pivoted for movement with respect to the said butt-unit; of locking-means for locking the two said units in normal axial alignment, including a manually-operated top-lever; a firing-member; means for urging said firing-member forwardly into firing position; fire-control means including a trigger, a firing-member stop-element integral with said trigger and arranged in the normal position of said trigger to extend in front of said firing-member, a trigger-spring arranged normally to urge said trigger forwardly so as to hold its firing-member stop-element in the path of movement of said forwardly-movable firing-member, and a sear carried by said trigger, said sear being arranged normally to engage said firing-member to hold the latter rearwardly in cocked position; and safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing position and the consequent discharge of said firearm by inadvertent disengagement of said sear from said firing-member.

3. In a breakdown firearm, the combination with a butt-unit and a barrel-unit pivoted for movement with respect to the said butt-unit; of locking-means for locking the two said units in normal axial alignment, including a manually-operated top-lever; a firing-member; means for urging said firing-member forwardly into firing position; fire-control means including a trigger, a firing-member stop-element integral with said trigger and arranged in normal position of said trigger to extend in front of said firing-member and a sear carried by said trigger, said sear being arranged normally to engage said firing-member to hold the latter rearwardly in cocked position; safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing position and the consequent discharge of said firearm by inadvertent disengagement of said sear from said firing-member; and a safety-slide operable independently of said safety-bar and arranged to positively actuate said trigger-locking lever to move the latter into locking engagement with said trigger.

4. In a breakdown firearm, the combination with a butt-unit and a barrel-unit pivoted for movement with respect to the said butt-unit; of locking-means for locking the two said units in normal axial alignment, including a manually-operated top-lever; a firing-member; means for urging said firing-member forwardly into firing position; fire-control means including a trigger, a firing-member stop-element integral with said

trigger and arranged in the normal position of said trigger to extend in front of said firing-member and a sear carried by said trigger, said sear being arranged normally to engage said firing-member to hold the latter rearwardly in cocked position; safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing position and the consequent discharge of said firearm by inadvertent disengagement of said sear from said firing-member; a safety-slide operable independently of said safety-bar and arranged to positively actuate said trigger-locking lever to move the latter into locking engagement with said trigger; and a detent associated with said safety-slide arranged to hold the latter and said trigger-locking lever in trigger-locking position as said trigger-locking lever is moved into engagement with said trigger by said safety-bar.

5. In a breakdown firearm, the combination with a butt-unit and a barrel-unit pivoted for movement with respect to the said butt-unit; of locking-means for locking the two said units in normal axial alignment, including a manually-operated top-lever; a firing-member; a spring for urging said firing-member forwardly into its firing position; fire-control means including a trigger, a firing-member stop-element integral with said trigger and arranged in the normal position of said trigger to extend in front of said firing-member and a sear carried by said trigger, said sear being arranged normally to engage said firing-member to hold the latter rearwardly in cocked position; safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing position and the consequent discharge of said firearm by inadvertent disengagement of said sear from said firing-member; and resilient-means associated with said safety-bar arranged normally to urge said safety-bar forwardly out of engagement with said trigger-locking lever.

6. In a breakdown firearm, the combination with a butt-unit and a barrel-unit pivoted for movement with respect to the said butt-unit; of locking-means for locking the two said units in normal axial alignment, including a manually-operated top-lever; a firing-member; means for urging said firing-member forwardly into firing position; fire-control means including a trigger, a firing-member stop-element integral with said trigger and arranged in the normal position of said trigger to extend in front of said firing-member and a sear carried by said trigger, said sear being arranged normally to engage said firing-

member to hold the latter rearwardly in cocked position; safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing position and the consequent discharge of said firearm by inadvertent disengagement of said sear from said firing-member; and resilient-means carried by said safety-bar arranged normally to urge said safety-bar forwardly so as to resiliently hold said top-lever in normal unit-locking position and to disengage said safety-bar from said trigger-locking lever.

7. In a breakdown firearm, the combination with a butt-unit and a barrel-unit pivoted for movement with respect to the said butt-unit; of locking-means for locking the two said units in normal axial alignment, including a manually-operated top-lever; a firing-member; means for urging said firing-member forwardly into firing position; fire-control means including a trigger, a firing-member stop-element integral with said trigger and arranged in the normal position of said trigger to extend in front of said firing-member and a sear carried by said trigger, said sear being arranged normally to engage said firing-member to hold the latter rearwardly in cocked position; safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing-position and the consequent discharge of said firearm by inadvertent disengagement of said sear from said firing-member; and cam-means associated with said firing-member, said cam-means being arranged to be engaged by the said firing-member stop-element of said trigger following the release of said firing-member to retract the latter.

8. In a breakdown firearm, the combination with a butt-unit and a barrel-unit pivoted for movement with respect to the said butt-unit; of locking-means for locking the two said units in normal axial alignment, including a manually-operated top-lever; a firing-member having a breast-portion and a cam-surface beneath said breast-portion; a spring for urging said firing-member forwardly into its firing position; fire-control means including a trigger, a firing-member stop-element integral with said trigger and arranged in the normal position of said trigger to extend immediately opposite the breast-portion of said firing-member and a sear carried by said trigger, said sear being arranged normally to engage said firing-member to hold the latter rearwardly in cocked position; and safety-means including a trigger-locking lever and a safety-bar, said safety-bar being cooperatively associated with said top-lever and said trigger-locking lever

whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof immediately opposite the breast-portion of said firing-member thereby to prevent its forward movement into firing position and the consequent discharge of said firearm by inadvertent disengagement of said sear from said firing-member, the said firing-member stop-element of said trigger being arranged to engage the cam-surface beneath the said breast-portion of said firing-member following the release thereof to retract said firing-member.

9. In a breakdown firearm, the combination with a butt-unit having a firing-pin aperture and a barrel-unit pivoted for movement with respect to said butt-unit; of locking-means for locking the two said units in normal axial alignment, including a manually-operated top-lever; a firing-member including a firing-pin and having a breast-portion and a cam-surface beneath said breast-portion; a spring for urging said firing-member forwardly into its firing position, in which position said firing-pin is adapted to project through the firing-pin aperture of said butt-unit; fire-control means including a trigger, a firing-member stop-element integral with said trigger and arranged in the normal position of said trigger to extend immediately opposite the breast-portion of said firing-member and a sear carried by said trigger, said sear being arranged normally to engage said firing-member to hold the latter rearwardly in cocked position; and safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof immediately opposite the breast-portion of said firing-member thereby to prevent its forward movement into firing position and the consequent discharge of said firearm by inadvertent disengagement of said sear from said firing-member, the said firing-member stop-element of said trigger being arranged to engage the cam-surface beneath the said breast-portion of said firing-member following the release thereof to retract said firing-member and hence withdraw the said firing-pin from the firing-pin aperture of said butt-unit.

10. In a breakdown firearm, the combination with a butt-unit and a barrel-unit pivoted for movement with respect to said butt-unit; of locking-means for locking the said units in normal axial alignment, including a manually-operated top-lever; a firing-member; a spring for urging said firing-member forwardly into its firing position; fire-control means including a trigger, a firing-member stop-element integral with said trigger and arranged in the normal position of said trigger to extend in front of said firing-member; a sear pivotally supported on said trigger and a sear-spring carried by said trigger and arranged normally to urge said sear forwardly so as to engage said firing-member and hold the latter rearwardly in cocked position; and

safety-means including a trigger-locking lever and a safety-bar, the said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal position and hence positively hold the firing-member stop-element thereof in front of said firing-member thereby to prevent its forward movement into firing position and the consequent discharge of said firearm by inadvertent disengagement of said sear from said firing-member.

11. In a breakdown firearm, the combination with a butt-unit and a barrel-unit pivoted for movement with respect to said butt-unit; of locking-means for locking the said units in normal axial alignment, including a manually-operated top-lever; a firing-member; a spring for urging said firing-member forwardly into its firing position; fire-control means including a trigger, a firing-member stop-element integral with said trigger and arranged in the normal position of said trigger to extend in front of said firing-member, a sear pivotally supported on said trigger, a sear-spring carried by said trigger arranged normally to urge said sear forwardly so as to engage said firing-member and hold the latter rearwardly in cocked position and a shoulder on said trigger constructed and arranged to cooperatively engage a shoulder on said sear when said trigger is pulled rearwardly so as to positively withdraw said sear from engagement with said firing-member for discharging said firearm; and safety-means including a trigger-locking lever and a safety-bar, the said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger and hold the firing-member stop-element thereof in front of said firing-member thereby to prevent its forward movement into firing position and the consequent discharge of said firearm by inadvertent disengagement of said sear from said firing-member.

12. In a breakdown firearm, the combination with a butt-unit having an aperture in its top wall and a barrel-unit pivoted for movement with respect to the said butt-unit; of locking-means for locking the two said units in normal axial alignment including a manually-operated top-lever, said top-lever having a post provided with a recess in its side wall and arranged to pivotally engage in the aperture of said butt-unit; fire-control means including a trigger, a trigger-locking lever movable to engage and disengage said trigger, and a safety-bar, said safety-bar being movably mounted between said top-lever and said trigger-locking lever and adapted to form a connection therebetween when said trigger-locking lever is disengaged from said trigger whereby operation of said top-lever to unlock said barrel-unit and butt-unit automatically actuates said safety-bar thereby simultaneously moving said trigger-locking lever into engagement with said trigger to lock the latter; and a spring carried by said safety-bar arranged to hold said safety-bar in sliding engagement with the underside of the said top wall of the said butt-unit and nor-

mally to hold the forward end of said safety-bar in the recess of said top-lever post to lock the latter in the aperture of said top wall and the rear end of said safety-bar out of engagement with the said trigger-locking lever.

13. In a breakdown firearm, the combination with a butt-unit having an aperture in its top wall and a barrel-unit pivoted for movement with respect to the said butt-unit; of locking-means for locking the two said units in normal axial alignment including a manually-operated top-lever, said top-lever having a post provided with a recess in its rear wall and arranged to pivotally engage in the aperture of said butt-unit; fire-control means including a trigger, a trigger-locking lever movable to engage and disengage said trigger, and a safety-bar, said safety-bar being movably mounted between said top-lever and said trigger-locking lever and adapted to form a connection therebetween when said trigger-locking lever is disengaged from said trigger whereby operation of said top-lever to unlock said barrel-unit and butt-unit automatically actuates said safety-bar thereby simultaneously moving said trigger-locking lever into engagement with said trigger to lock the latter; a spring carried by said safety-bar arranged to hold said safety-bar in sliding engagement with the underside of the said top wall of the said butt-unit and normally to hold the forward end of said safety-bar in the recess of said top-lever post to lock the latter in the aperture of said top wall and the rear end of said safety-bar out of engagement with the said trigger-locking lever; and a safety-slide operable both manually and by said safety-bar to move said trigger-locking lever into locking engagement with said trigger.

14. In a breakdown firearm, the combination with a butt-unit having an aperture in its top wall and a barrel-unit pivoted for movement with respect to the said butt-unit; of locking means for locking the two said units in normal axial alignment including a manually-operated top-lever, said top-lever having a post provided with a recess in its rear wall and arranged to pivotally engage in the aperture of said butt-unit; fire-control means including a trigger, a trigger-locking lever movable to engage and disengage said trigger, and a safety-bar, said safety-bar being movably mounted between said top-lever and said trigger-locking lever and adapted to form a connection therebetween when said trigger-locking lever is disengaged from said trigger whereby operation of said top-lever to unlock said barrel-unit and butt-unit automatically actuates said safety-bar thereby simultaneously moving said trigger-locking lever into engagement with said trigger to lock the latter; a spring carried by said safety-bar arranged to hold said safety-bar in sliding engagement with the underside of the said top wall of the said butt-unit and normally to hold the forward end of said safety-bar forwardly in the recess of said top-lever post to lock the latter in the aperture of said top wall and the rear end of said safety-bar forwardly out of engagement with the said trigger-locking lever; a safety-slide operable both manually and by said safety-bar to move said trigger-locking lever into locking engagement with said trigger; and a detent associated with said safety-slide to hold the latter and said trigger-locking lever in trigger-locking position as said trigger-locking lever is moved into engagement with said trigger by said safety-bar.

15. In a firearm, the combination with a frame;

a fixed strut in said frame having a guide-aperture; a firing-member pivotally mounted in said frame; fire-control means including a trigger-and-sear assembly arranged to hold said firing-member in cocked position; and means to urge said firing-member forwardly into firing position when released by said trigger-sear assembly, said means comprising a link slidably supported at its rear end in the guide-aperture of said strut and having a fastening-member at its forward end to secure said link to said firing-member, a shoulder at the opposite end of said link, a collar slidably mounted on said link between said fastening-member and said shoulder and arranged to engage said apertured strut, and a firing-member spring mounted on said link, said spring being arranged to engage at its forward end against the fastening-member of said link and at its rear end against said slidable collar to hold the latter in engagement with said apertured strut, said spring being adapted to be held under compression between said fastening-member and said slidable collar when said firing-member is in cocked position and to be decompressed by the displacement of said collar out of engagement with said apertured strut and rearwardly on said link into engagement with the shoulder thereof following the release of said firing-member and its movement forwardly into firing position thereby to permit said firing-member to swing back freely from its firing position.

16. In a firearm, the combination including a firing-member; resilient-means for urging said firing-member forwardly into its firing position, said resilient-means being arranged to be compressed when said firing-member is in its cocked position and to be decompressed when said firing-member is in its forward firing position, so as to free said firing-member and permit the latter to move back freely from its firing position; fire-control means including a trigger having a firing-member stop-element integral therewith and arranged in the normal position of said trigger to extend in front of said firing-member; and a sear actuated by said trigger, said sear being arranged normally to engage said firing-member to hold the latter rearwardly in cocked position and to release said firing-member when said trigger is pulled to permit said firing-member to be moved forwardly by said resilient-means into firing position, and cam-means associated with said firing-member, said cam-means being arranged to be engaged by the said stop-element of said trigger when said firing-member is in its free firing position, to retract the latter.

17. In a breakdown firearm, the combination including a firing-member; resilient-means for urging said firing-member forwardly into its firing position, said resilient-means being arranged to be compressed when said firing-member is in its cocked position and to be decompressed when said firing-member is in its forward firing position, so as to free said firing-member and permit the latter to move back freely from its firing position; fire-control means including a trigger having a firing-member stop-element integral therewith and arranged in the normal position of said trigger to extend in front of said firing-member; a trigger-spring to hold said trigger in its normal position; a sear carried by said trigger, said sear being arranged normally to engage said firing-member to hold the latter rearwardly in cocked position and to release said firing-member when said trigger is pulled to permit said firing-member to be moved forwardly by said resil-

ient-means into firing position; and a cam-surface on said firing-member, said stop-element being arranged to be urged by said trigger-spring into camming engagement with the cam-surface of said firing-member when the latter is in its free firing position, to retract the latter.

18. In a breakdown firearm, the combination including a butt-unit having an apertured standing-breech and a barrel-unit pivoted for movement with respect to the said butt-unit; a pivoted firing-member including a firing-pin; resilient-means for urging said firing-member forwardly into its firing position to project said firing-pin through the aperture of said standing-breech, said resilient-means being constructed and arranged to be compressed when said firing-member is held in its cocked position and to be decompressed when said firing-member is in its forward firing-position so as to free said firing-member and permit the latter to swing back freely from its firing position and thereby withdraw said firing-pin into the aperture of said standing-breech; fire-control means including a trigger having a firing-member stop-element integral therewith, and a trigger-spring arranged normally to urge said trigger forwardly so as to hold its stop-element in front of the said firing-member; a sear carried by said trigger, said sear being arranged normally to engage said firing-member to hold the latter rearwardly in cocked position; and a cam-surface on said firing-member, said trigger-spring being constructed and arranged to urge the said stop-element of said trigger into camming engagement with the cam-surface of said firing-member following the release thereof by said sear, to automatically retract the said firing-member and hence withdraw the firing-pin into the aperture of said standing-breech.

19. In a breakdown firearm, the combination including a butt-unit having an apertured standing-breech and a barrel-unit pivoted for movement with respect to the said butt-unit; locking-means for locking the two said units in normal axial alignment including a manually-operated top-lever; a pivoted firing-member including a firing-pin; resilient-means for urging said firing-member forwardly into its firing position to project said firing-pin through the aperture of said standing-breech, said resilient-means being arranged to be compressed when said firing-member is in its cocked position and to be decompressed when said firing-member is in its forward firing position, so as to free said firing-member and permit the latter to swing back freely from its firing position and thereby withdraw said firing-pin into the aperture of said standing-breech; fire-control means including a trigger having a firing-member stop-element integral therewith; a trigger-spring arranged normally to urge said trigger forwardly so as to hold its firing-member stop-element in the path of movement of said forwardly movable firing-member; a sear carried by said trigger, said sear being arranged normally to engage said firing-member to hold the latter rearwardly in cocked position; safety-means including a trigger-locking lever and a safety-bar, said safety-bar being cooperatively associated with said top-lever and said trigger-locking lever whereby operation of said top-lever to unlock said barrel-unit and butt-unit automatically actuates said safety-bar, the latter being arranged simultaneously to move said trigger-locking lever into engagement with said trigger to lock said trigger in its normal posi-

tion and hence positively hold the firing-member stop-element thereof in front of said firing-member thereby to prevent its forward movement into firing position and the consequent discharge of said firearm by inadvertent disengagement of said sear from said firing-member; and a cam-surface on said firing-member, said trigger-spring being arranged normally to urge the said stop-element of said trigger into camming engagement with the cam-surface of said firing-member when the latter is in its free firing position, to retract the latter following the release of the firing-member by said sear and hence to withdraw the firing-pin into the aperture of the standing-breech.

20. In a firearm, the combination with a frame; a firing-member movably mounted therein, said firing-member including a link having a displaceable collar; fire-control means including a trigger-and-sear assembly arranged to hold said firing-member in cocked position; means to urge said firing-member forwardly into firing position when released by the said trigger-and-sear assembly, said means comprising a firing-member spring mounted on said firing-member link and arranged to engage at its forward end against said firing-member and at its rear end against the displaceable collar of said link; and an abutment fixed to said frame rearwardly of said firing-member, said abutment constituting a stop for said collar and having a guide-aperture therein for accommodating the rear end of said link as said firing-member is moved rearwardly relative to said abutment, said spring being adapted to move said collar against the stop-abutment as said link is displaced rearwardly relative to said collar and to be compressed between said collar and the rearwardly-moving firing-member as the latter is moved into cocking engagement with said trigger-and-sear assembly, said spring being decompressed on release of said firing-member by bodily movement of said link forwardly with said firing-member out of engagement with said abutment and by the attendant displacement of said collar rearwardly on said link thereby to permit said firing-member to move back freely from its firing position.

21. In a firearm, the combination with a frame; a firing-member movably mounted therein, said firing-member including a link having a displaceable collar; fire-control means including a trigger-and-sear assembly arranged to hold said firing-member in cocked position; means to urge said firing-member forwardly into firing position when released by the said trigger-and-sear assembly, said means comprising a firing-member spring mounted on said firing-member link and arranged to engage at its forward end against said firing-member and at its rear end against the displaceable collar of said link; an abutment fixed to said frame rearwardly of said firing-member, said abutment constituting a stop for said collar and having a guide-aperture therein for accommodating the rear end of said link as said firing-member is moved rearwardly relative to said abutment, said spring being adapted to move said collar against the stop-abutment as said link is displaced rearwardly relative to said collar and to be compressed between said collar and the rearwardly-moving firing-member as the latter is moved into cocking engagement with said trigger-and-sear assembly, said spring being decompressed on release of said firing-member by bodily movement of said link forwardly with said firing-member out of engagement with said abutment and by the attendant displacement of said collar rearwardly on said link thereby to permit said firing-member to move back freely from its firing position; and a shoulder at the rear end of said link constituting a stop to limit the rearward displacement of said collar thereon.

ALFRED CURCI.
